UNITED STATES PATENT OFFICE

FRANK C. PICKARD, OF ERIE, PENNSYLVANIA, ASSIGNOR TO THE STANDARD STOKER COMPANY, INCORPORATED, A CORPORATION OF DELAWARE

STOKER

Application filed July 23, 1929. Serial No. 380,433.

This invention relates to stokers of the scatter feed type and particularly to such as embody means for raising fuel through a conduit exteriorly of the firebox to a point 6 above the level of the fire and delivering the same to the firebox through an opening in the backwall and there projecting the fuel over the fire by means of jets of pressure fluid.

10 In stokers of this type it is desirable to locate the jet structure or distributor head in the feeding system rearward of the firebox backwall to permit its replacement being made readily and to have space to extend 15 conduits or suitable pipes from a source of supply such as a manifold on the firebox backwall to the lower portion of the distributor head, and also to have it mounted in any position such that it will not be subjected to 20 the heat of the fire. The distributor head and its associated parts are so arranged as to provide a passage for entrance of outside air to the firebox forward of the distributor head and beneath its adjoining distributor 25 member for the purpose of cooling the stoker parts to protect those portions exposed to the fire. In practice the manifold is disposed above and to one side of the distributor head and is mounted in a horizontal plane on the 30 backhead within easy reach of the operator, the supply pipes extending downwardly from the manifold to a point below the distributor head, there they are bent laterally and extend to a position directly beneath the 35 distributor head and each pipe is then turned upwardly and fitted into a threaded opening in the bottom end of the distributor head. From this description of past practice it will be understood that the supply pipes extending 40 from the left side of the manifold communicate with the jet passages in the right side of the distributor head, thus the pipes to the left side of the manifold supply the pressure fluid and are adapted to control the 45 distribution of the fuel over the right side of the firebox and conversely the pipes to the right side of the manifold are adapted for the control of the distribution of fuel to the left side of the firebox.

50 This arrangement for the control of the

projection and distribution of fuel over the fire is very confusing to the operator, and the supply piping and the position of the distributor head and its associated parts makes it very difficult to replace the distributor head or to repair or replace the piping; and the arrangement is also such that the supply pipes obstruct the free passage of the cooling air beneath one side of the distributor member with the result that practically 55 only one side of the member is sufficiently protected from the heat of the fire to prevent rapid deterioration caused by the heat and the flame of the fire burning away the unprotected exposed portion of the member. 60

65 The present invention eliminates all the difficulties experienced in past practice and its objects are to provide a new and novel distributor head and a simplified arrangement of its associated parts such as will overcome past difficulties and present other advantages.

70 The advantages of the invention and the improved distributor head are all particularly described in the following specification 75 as illustrated on the accompanying drawings, in which

Figure 1 is a fragmentary detail vertical central section through the rear portion of a locomotive with the stoker of the invention applied thereto and being in similar section;

Figure 2 is a rear elevation of the parts shown in Figure 1 and taken in section in a vertical plane on the line 2—2 of Figure 1;

Figure 3 is an enlarged view in section of 85 the distributor head of Figure 1 and its associated parts;

Figure 4 is a vertical section taken on the line 4—4 of Figure 3 through the distributor head;

Figure 5 is a perspective view of the improved distributor head of the invention; and

Figure 6 is a section taken in a horizontal plane on the line 6—6 of Figure 3.

90 On the drawings the locomotive is generally indicated as at 10, its firebox at 11 having the backwall 12 with the firing opening 13 therein at a point above the grates 14. The locomotive is provided with the usual cab 15 having a floor or firing deck 16 which is in 100

substantial alignment with the floor 17 of the tender indicated as a whole at 18.

That portion of the stoker shown comprises a forward section or rising conduit member 5 20 fixed to the backwall 12 and at its upper end communicating with the firing opening 13 and at its lower end receiving the forward section 21 of a telescoping conduit 22 which as is well understood leads forwardly from a 10 rearward conduit portion located beneath the floor 17 of the tender. The fuel is conveyed forwardly through the intermediate conduit 22 by the screw conveyer 23 which delivers the fuel into the riser conduit 20 and forces 15 it therethrough delivering it into the firing opening 13. The fuel from the member 20 is delivered onto a distributor member or plate 24 extending through the firing opening 13 and which plate is detachably secured at 20 its rearward face to the member 20 by any suitable fastening means.

The fuel is projected across the distributor member and scattered over the firebox by a substantially fan-shaped pressure fluid blast 25 issuing from the nozzles or jet openings 25 of a plate like distributor head 26 disposed rearwardly of the distributor member and also of the firebox backwall and is received in the notch or slot 27 in the floor portion of the 30 conduit 20. This distributor member extends somewhat above the floor of the conduit and to a height suitable to permit the discharge of the pressure fluid blast across the plate portion of the distributor member. 35 The distributor head is fixed in this position to the conduit 20 by headed screws 28 through its attaching arms or lugs 29, 29a extending laterally from the upright side walls of the distributor head. The width of the distributor 40 head may be equal to that of the conduit 20 but in its preferred construction the head is narrower than the conduit and is disposed centrally thereof as is best shown in Figure 2.

The jet openings 25 in the forward face of 45 the distributor head lead from a plurality of independent passages 30 separated laterally from one to the other and being in the same vertical plane. Preferably, five such passages are provided, the center passage and its 50 jet openings are adapted to project jets of pressure fluid over the center of the firebox, the passage at the left and right sides of the head and their respective jet openings which are inclined towards their respective sides of 55 the firebox are adapted to project jets of pressure fluid to the left and right rear side portions of the firebox and together with the distributor member 24 direct and are adapted to control the delivery of the fuel to the back 60 corners of the firebox; and the intermediate passages and their laterally directed jet openings are adapted to project jets of pressure fluid to the front and front side portions of the fire, the combined jets of pressure fluid 65 form a fan-shaped blast for projecting and

scattering the fuel over the fire and which blast in cooperation with the directing pockets 31 of well understood form of the member 24 function to spread the fuel uniformly to all parts of the fire. As can be best observed from Figures 4 and 6, the jet openings of the various passages are substantially in the same horizontal plane and the jet openings to each side of the center jet opening in the center passage are inclined laterally whereby the fan-shaped blast is formed. 70

Each of the passages at their lower and inner ends open laterally as at 32, preferably, facing the left side of the distributor head, these openings 32 being threaded to receive 80 the conduit or supply pipes 33 leading from the manifold 34 disposed on the backwall above and to one side of the distributor head. The threaded openings 32 are stepped rearwardly of the front wall of the distributor head, some being in the same horizontal plane while others are spaced in the planes above or below. This arrangement is advantageous in that the nipple portion 35 of the supply pipes can be fitted into or removed from the distributor head from a position to one side of the stoker by breaking the supply lines at the coupling or union connections 36 without it being necessary to remove the conduit or to remove the stay bolt caps or appliances on the backhead. There is also the further advantage in that the position of the distributor head provides an entrance 37 for the admission of outside air to the fire beneath the distributor member 24 for cooling the same and which entrance is not in any way obstructed by the supply pipes by reason of their position rearward of the front wall of the distributor head. 90

The manifold is fixed to the firebox backwall by headed screws as at 38 and a pressure fluid, such as steam, is brought to the manifold from the locomotive boiler or any other source of supply through the intake line 39. The pipes leading from the manifold are each provided with a manually adjustable valve 40 and any suitable coupling or connecting members as may be needed to permit the pipes to be assembled in the position shown in Figure 2. 105

From Figures 2 and 5, it is obvious that the supply pipe leading to the center passage of the distributor head is the center pipe leading from the manifold and that left and right intermediate supply lines communicate with the corresponding left and right intermediate passages in the distributor head and that the pipes at either end of the manifold lead to the corresponding extreme end passages of the distributor head. 110

In the use of the invention the fuel conveyed through the stoker conduit system is delivered through the conduit 20 on to the distributor member 24 within the zone of action on the fan-shaped blast discharging 120

from the distributor head 26. The blast blows the coal across the distributor plate and by reason of its shape and the form of the distributor member the fuel is spread 5 uniformly over all parts of the fire. The distribution of the fuel is under the control of the operator who may spread the fuel uniformly over the fire by the proper adjustment of the valves 40 of the supply pipes 33, or 10 the supply of fuel to various portions of the fire may be varied by adjustment of the valves 40 to vary the intensity of the pressure fluid jets issuing from the nozzles 25 of the passages in the distributor head controlling 15 that portion of the fire over which a change in the spreading of the fuel is brought about if desired. For instance, if the operator desires to effect a change in the spreading of the fuel to the left rear corners of the 20 firebox this can be done by adjusting the valve in the supply line to the extreme left of the manifold and likewise the operator controls the spreading of the fuel over the side and center portions of the fire by adjustment 25 of the valves in the intermediate and center supply lines.

It will be observed that the arrangement of the supply and control of the pressure fluid to the distributor head is readily understood and is not likely to confuse the stoker operator as happens in past practice.

It will also be seen that the arrangement of the distributor head and its piping permits a free and unobstructed flow of outside air to the firebox for cooling the stoker parts and also that the arrangement of the parts is such that the distributor head can be readily applied or removed.

The invention consists in the peculiar construction of the distributor head and in the arrangement of the parts and supply piping or conduits as defined in the appended claims.

I claim:

1. In combination, a locomotive having a firebox provided with a backwall, a distributor member, a distributor head separate from said member and mounted at the rear thereof, said head being provided with a plurality of separated independent passages, each passage having an admission opening located rearward of said backwall and directed laterally thereof, the axis of each admission opening lying in a vertical plane which extends transversely of the firebox, said admission openings all being directed toward the same side of said firebox, a manifold on said backwall located laterally of said head on the same side thereof toward which the admission ends of the passages are directed, conduits for connecting said manifold to said passages, respectively, and manually controlled valves for said conduits.

2. In combination, a locomotive having a firebox provided with a backwall, a fuel conduit for delivering fuel to said firebox, a distributor head separate from said conduit and mounted in the floor thereof to extend exteriorly of the firebox, said head arranged to distribute fuel over the firebox and comprising a body portion having a plurality of walled independent passages, each passage having an admission opening located rearward of said backwall and directed laterally thereof, the axis of each admission opening lying in a vertical plane which extends transversely of the firebox, said admission openings all being directed toward the same side of said firebox, a manifold on one side of said distributor head for containing a pressure fluid, said manifold having openings arranged from side to side to correspond with the passages of said head, a plurality of pipes, each of which connects the openings of said manifold with the respective passage of said head, and a manually operated valve in each of said pipes.

3. In combination, a locomotive having a firebox provided with a backwall having an opening therethrough, a fuel conduit for delivering fuel to said opening, a distributor head mounted in the floor of said fuel conduit for distributing fuel over the grates of said firebox, said head comprising a body portion having passages at the right and left sides thereof for distributing fuel to the right and left sides of said firebox, respectively, each of said passages having an admission opening located rearward of said backwall and directed laterally thereof, the axis of each admission opening lying in a vertical plane which extends transversely of the firebox, said admission openings all being directed toward the same side of said firebox, a manifold secured to said backwall and located above and laterally of said head, said manifold including openings at the right and left sides thereof, conduits for connecting the opening at the right side of said manifold with the opening in the passage at the right side of said head and the opening at the left side of the manifold with the opening in the passage at the left side of said head, respectively, and means for independently controlling the flow of pressure fluid through each of said passages.

4. In combination, a locomotive having a firebox provided with a backwall having an opening therethrough, a fuel conduit for delivering fuel to said opening, a distributor head mounted in the floor of said fuel conduit for distributing fuel over the grates of said firebox, said head having a plurality of passages for directing a pressure fluid for distributing fuel to the side and intermediate portions of said firebox, each of said passages having an admission opening located rearward of the backwall and directed laterally thereof, the axis of each admission opening lying in a vertical plane which extends transversely of the firebox, said admis-

- sion openings all being directed to the same side of said firebox, a manifold separate from and being located above and laterally of said head, said manifold including openings which
- 5 correspond to the passages of the distributor head, conduits for connecting the corresponding openings and passages whereby the pressure fluid passing from said manifold through an intermediate opening or an opening at
- 10 either side thereof will project fuel to an intermediate or the respective side portion of said firebox, and means for independently controlling the flow of pressure fluid through said conduits.
- 15 5. In combination, a locomotive having a firebox provided with a backwall having a firing opening therethrough, a fuel conduit for delivering fuel to said opening, a distributor head mounted in the floor of said fuel
- 20 conduit for distributing fuel over the grates of said firebox, said head having a plurality of passages for directing a pressure fluid for distributing fuel to the side and intermediate portions of the firebox, each of said passages
- 25 having an admission opening located rearward of the backwall and directed laterally thereof, the axis of each admission opening lying in a vertical plane which extends transversely of the firebox, said admission openings all being directed to the same side of
- 30 said firebox, a manifold separate from and being located above and laterally of said head, said manifold including openings which correspond to the passages of the distributor head, conduits connecting the openings of said manifold with respective passages of said head, and valves in said conduits arranged to correspond with said passages whereby when an intermediate valve or
- 35 a valve at either side thereof is opened, fuel will be projected to an intermediate or the respective side of said firebox.
- 40 6. As an article of manufacture, a distributor head for stokers comprising a body portion, said body portion including a front wall, a rear wall and side walls connecting said front and rear walls, and a plurality of passages in said body portion for receiving a pressure fluid, the front wall being provided
- 45 with jet openings in communication with said passages, each of said passages at an end remote from said jet openings, having an admission opening, said admission openings all being directed toward the same side wall of
- 50 said head.
- 55 7. As an article of manufacture, a distributor head for stokers comprising a body portion, said body portion including a front wall, a rear wall and side walls connecting said front and rear walls, attaching arms extending outwardly from said body portion, and a plurality of passages in said body portion for receiving a pressure fluid, the front wall being provided with radiating jet openings, each of said passages at an end remote

from said jet openings having a screw threaded admission opening, said admission openings all being directed toward the same side wall of said head.

In testimony whereof I affix my signature. 70
FRANK C. PICKARD.
